UNITED STATES PATENT OFFICE.

OLIVER H. KINGSLAND, OF NEW YORK, N. Y., ASSIGNOR TO HENRY B. NEWHALL, OF PLAINFIELD, NEW JERSEY.

DOOR-BINDER.

SPECIFICATION forming part of Letters Patent No. 630,811, dated August 8, 1899.

Application filed January 25, 1898. Renewed February 18, 1899. Serial No. 706,066. (No model.)

To all whom it may concern:

Be it known that I, OLIVER H. KINGSLAND, a citizen of the United States, residing at New York, (Brooklyn,) in the county of Kings and State of New York, have invented a certain new and useful Improvement in Door-Binders, of which the following is a specification, reference being had to the drawings accompanying and forming a part of the same.

10 The present invention relates to improvements in door-binders—that is, in devices for holding a door, especially a fire-door, tightly against the walls of the door-space or other passage through the walls—and the invention 15 relates particularly to that form or arrangement of door-binders, known as "duplicate" or "multiple" binders, used for the purpose of holding doors, one arranged to close a door-space on the inside of the building-wall and 20 one to close the space from the outside of the wall.

The invention consists of a door-binder of the kind indicated, the buffer, binder, or door engaging and holding part of which is adjustably mounted or carried on the part of the 25 binder which is secured to the walls of the door-space.

Referring to the drawings, Figure 1 indicates a plan view (a view looking down on the 30 upper edge of the doors) of one form of door-binder mechanism embodying my invention, the walls of the door-space being shown in horizontal section and one door being shown closed, while the other is in open position. 35 Fig. 2 is an elevation view of a binder for holding the lower edge of the door. Fig. 3 is a vertical section of the same on the plane *a a*. Fig. 4 is a plan view of the same with the adjustable binding part removed. Fig. 40 5 is a modification to be more fully explained in the following description.

Referring to the drawings in detail, A represents a doorway-space, and B B side or vertical walls inclosing the same.

45 C represents an outer door, and D an inner door, the latter being shown in closed position, while the former is in open position. These doors may be hung and operated by any proper means, though ordinarily they 50 would be hung on trolley-tracks and so arranged or provided with operating mechan-

ism that they will automatically close, as in the case of a high or unsafe temperature in the neighborhood of the doorway-space, various means for causing such doors to remain 55 open and to automatically close in event of fire occurring near the doorway-space being well known.

E represents one of the binders, which preferably is in the form of the frustum-bracket shown, carrying the friction roll or wheel F, and is mounted on the toothed or notched base-plate G, which base-plate is adjustable on the foot H of the side bar I, attached to and arranged at right angles to the slide-bar J, said foot H being also provided with teeth K and notches L that mesh with the notches and teeth of the base of the binder, the binder being held in fixed position on the foot by a screw M and its base being guided, when 70 moved for adjustment, by the upwardly-projecting rib N.

When this device is applied to the walls of, say, a fire-door space, the slide-bar J of one such binder mechanism is fixed to the inner 75 or door-space face of one of the walls, while the side bar bears against the outer face of the wall, as seen in Fig. 1, and another binder mechanism of similar form is fixed to the other side of the wall, the two slide-bars lying one 80 upon the other, screw-bolts O being used to hold the bars in place on the wall, which bolts pass through holes P and Q in the slide-bars, one or both of which holes may be elongated, as shown in Fig. 2, for the purpose of adjusting 85 the bars to different thicknesses of door-space walls.

In case of applying this mechanism, as shown in Fig. 1, it is supposed that the binder engages the lower edge of the door, the thickness of the base of the binder and the foot of the side bar being together about the thickness of the ordinary door-sill. Assuming that the binder is adjusted so that the space between the periphery of its wheel and the 95 face of the side bar properly conforms to the thickness of the door, it will readily be seen that in case of a door closing its closing vertical and bottom edges will be guided by and brought to close contact with the side walls 100 of the door-space by the binder and its wheel, thus insuring that the door be held tightly

to the walls and prevented from springing or warping, so as to open the door-space. I apply this means of adjusting the binder on its support to binders of other forms—such, for instance, as to a binder used to hold the vertical edge of a door between its top and bottom. Thus in Fig. 5 I show slide-bars R and S of construction substantially as already described, but which carry side bars T, running horizontally instead of vertically, as in the case of Fig. 2, and these side bars are provided with teeth and notches U, which engage corresponding teeth and notches in the base V of the binder W, which binder is adapted in form and attachment to the door-space walls to serve as a buffer to stop the door as well as to bind its edge to the wall. By loosening the securing-bolt X this binder may be adjusted horizontally, so as to determine the extent that the edge of the door shall lap the walls. By these means I provide an adjustable support for a door-binder, whereby the binder can be readily adjusted on its supporting parts to the thickness of the door or to the extent of its wall-lap, as also the binder carrying parts of a duplicate arrangement of binder mechanisms may be made adjustable to suit different thicknesses of wall, so that one form or size of binder mechanism can be

utilized for various thicknesses of door-walls 30 and various thicknesses of doors.

What is claimed as new is—

1. A door-binder consisting essentially of a bar J adapted to be secured to the passage-face of a door-space wall, the side bar I secured at right angles thereto and adapted to bear upon one of the side faces of the wall and notched and toothed, and a binder device also notched and toothed and adjustably secured to said side bars, for the purpose set 40 forth.

2. In combination with a slide-bar J having the side bar I and foot H, the binder E adjustably secured to said foot by notched and toothed connections and provided with the 45 friction-wheel F, substantially as and for the purpose set forth.

3. In combination with the slide-bar J carrying a side bar I and foot H, the binder E having a notched and toothed connection with 50 said foot, and a rib N for guiding the binder when being adjusted, and means for fixedly securing said binder and foot together.

OLIVER II. KINGSLAND.
